UNITED STATES PATENT OFFICE.

JOHN COOPER, OF NEW YORK, N. Y.

DESIGN FOR A CHIMNEY-CAP SECTION.

SPECIFICATION forming part of Design No. 32,536, dated April 17, 1900.

Application filed March 22, 1900. Serial No. 9,810. Term of patent 14 years.

To all whom it may concern:

Be it known that I, JOHN COOPER, a citizen of the United States, residing at the city of New York, borough of Brooklyn, in the county 5 of Kings and State of New York, have invented and produced a new and original Design for a Chimney-Cap Section, of which the following is a specification.

Reference is to be had to the accompanying 10 drawings, forming a part of this specification, in which similar characters of reference indicate corresponding parts in both the figures.

Figure 1 is a perspective view of a chimney-cap section, showing my design; and Fig. 15 2 is a cross-section thereof.

The leading feature of my design for a chimney-cap section consists in a rectangular body portion 1, having an opening through it and having at one edge a flange 2, trans-

versely curved on its under side, and a transversely curved bead 3 at the opposite edge.

The flange 2 is shown as transversely curved on its upper side, and there is a less width of the material at the side where the flange is formed than at the opposite side.

Having described my invention, what I claim as new, and desire to secure by Letters Patent, is—

The design for a chimney - cap section as herein shown and described.

In testimony whereof I have signed my name to this specification in the presence of two subscribing witnesses.

JOHN COOPER.
